CONVERTIBLE ATHLETIC GARMENT

Louis Mintzes, Island Park, N. Y., assignor of
one-half to Jack Litt, Harrison, N. Y.

Application September 4, 1945, Serial No. 614,173

2 Claims. (Cl. 2-71)

1

This invention relates to garments having inverted pleats which are secured part way up to form a crotch and which are adapted for athletic or gymnasium use and convertible for street wear.

An object of this invention is to provide a convertible garment comprising an outer garment member having an integral crotch and having an integral ribbon-like member, the ribbon-like member comprising separable leg embracing portions and the separate portions being foldable into concealment within pockets, the pockets being secured to the inverted pleats.

Another object of this invention is to provide pairs of oppositely facing pockets and pairs of strip extensions extending from the respective pockets toward each other, whereby, upon securing the free end portions of each pair of the extensions there is formed a leg embracing member in each leg portion of the garment.

Another object of this invention is to provide improvements in a bifurcated garment having a crotch, and comprising fabric strips extending respectively from the front and rear of the garment, the said strips forming ribbon-like inner members positioned in substantially covering relation with the crotch and thereby effect concealment of the body portion of the wearer at the crotch.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a front elevation of the assembled garment showing a through opening at the lower portion of the garment, such as appears when the garment is used for athletic purposes, one of the leg-encircling portions of the garment being broken away to show one of the leg-embracing members in position over a thigh of the wearer.

Figure 2 is a cross-sectional view, the section being taken as on line 2-2 in Figure 1.

Figure 3 is a plan view of a garment panel showing one of its vertical edges folded over for forming an inverted pleat.

Figure 4 is a plan view of a section of fabric used for attachment to the folded panel shown in Figure 2 and having an integral strip ex-

2

tending in substantially right-angular relation therewith and used to form leg-embracing ribbon-like members.

Figure 5 is a plan view of the garment panel shown in Figure 3, with the section of fabric shown in Figure 4 stitched thereto.

In the illustrated embodiment of the invention, the numeral 10 indicates a convertible athletic garment comprising an upper body portion 11 and a skirt portion 12. The skirt 12 has inverted pleats 13, at the front and rear of the garment. The pleats are secured part way up to form a crotch 14 and two portions 15, 15 which freely encircle the legs of the wearer. The garment 10 comprises ribbon-like members 17, 17 inside the leg-encircling portions 15.

Figure 3 shows one of four panels 20 of which the garment is made. Each panel 20 has its vertical edge 21 folded over to provide a rectangular strip 22 or inner upright pleat member extending all the way from the top to the bottom of the panel.

Figure 4 shows a section of fabric 23 particularly designed for the purposes of this invention, four sections being required for a garment 10. Each section 23 comprises a rectangular portion 24 or outer upright pleat member extending all the way from the top to the bottom of the panel, and a horizontal strip 25 which extends substantially in right-angular relation with the portion 24. The strips 25 on the sections 23 serve in the formation of the ribbon-like members 17. Below the horizontal strip 25 is a free edge portion 27 which is in alignment with the left hand edge of the rectangular portion 24.

Figure 5 shows the garment panel 20 with the section 23 stitched thereto along the free edge 26 of the folded strip 22 all the way down and including the free edge portion 27. In this stitched position the rectangular portion 24 of the section of fabric 23 jointly with the folded strip 22, form half of an inverted pleat 13, best shown in Figure 2.

Each ribbon-like member 17 is formed of two strips 25. Buttons 31 and buttonholes 32 secure the free end portions of the strips 25 and the members 17 form leg-embracing means about each thigh of the wearer. The strips 25 extend an equal distance above and below the junction at the crotch.

At the end of each strip 25, where it is integral with a pleat 13, I provide a pocket 33, having an opening 34 which faces in a direction lengthwise of the strip. Each pocket is of a size 55 to permit a strip to be foldable into concealment

therein. When the free end portions of two strips 25 are secured in unitary relation, they embrace a thigh of the wearer and hold a portion of the garment at the crotch in substantially fixed position with relation to the thigh. This serves to effect concealment of the body portion of the wearer at the crotch.

It will thus be seen that there is provided a convertible athletic garment comprising thigh-embracing means whereby during exercising, when the free lower portion of the garment is raised and there is a tendency to expose the body portion of the wearer at the crotch the leg-embracing means come into play and prevent exposure of the body portion at the crotch.

Each leg-embracing ribbon-like member 17 is made of two separable strips of fabric 25 which are substantially of equal length so that pockets of one size may be used. The depth of each pocket 33 is made equal to one-half the length of a strip 25 and this permits each strip to be doubled and folded within a pocket.

When the strips 25 are folded into concealment within the pockets they lie flat and do not hinder walking or exercising by the wearer.

The successive steps whereby each strip is inserted into its pocket are as follows: The strip is doubled over upon itself, with the free edge of the strip positioned at the opening to the pocket. The user then opens the pocket and places the folded strip therein, close to an outer edge of one of the inverted pleats.

In the modified form of the invention incorporated in a garment called a "short," the portion 27 is removed up to the lower edge of the strip 25.

The disclosure herein shown may be applied to athletic garments, such as play suits, gymnasium suits, bowling dresses, cycling suits, skating suits, athletic shorts and bathing suits.

It is to be noted that each ribbon-like member 17 may be made of one piece. Also that the garment 10 may be made without the pockets 33. It is to be further noted that the sections 33 are normally inside the body of the garment.

In accordance with the patent statutes I have described and illustrated the preferred embodiment of my invention, but it will be understood that various changes and modifications can be made therein without departing from the spirit of the invention as defined by the appended claims.

I claim:

1. In an athletic garment having inverted front

and rear pleats, said pleats being united to form a crotch, each of said pleats comprising outer and inner upright pleat members, ribbon-like strips extending respectively from said inner pleat members, said ribbon-like strips being positioned adjacent said crotch and being movable into embracing relation with the thighs of the wearer, said ribbon-like strips in thigh embracing position causing a portion of each of said inner pleat members to be moved into superposeable covering relation with the body portion at said crotch, said ribbon-like strips in said thigh embracing position serving to retain said covering portions of said inner pleat members in said body covering relation and effect concealments of the body portion of the wearer at said crotch while said outer pleat members permit enlargement of said garment during exercising.

2. In an athletic garment having inverted front and rear pleats, said pleats being united to form a crotch, each of said pleats comprising outer and inner upright pleat members, ribbon-like strips extending respectively from said inner pleat members, said ribbon-like strips being positioned adjacent said crotch and being movable into embracing relation with the thighs of the wearer, said ribbon-like strips in thigh embracing position causing a portion of each of said inner pleat members to be moved into superposeable covering relation with the body portion at said crotch, said ribbon-like strips in said thigh embracing position serving to retain said covering portions of said inner pleat members in said body covering relation and effect concealments of the body portion of the wearer at said crotch while said outer pleat members permit enlargement of said garment during exercising, pockets secured to said pleat members and in alignment with said strips, and means for separating said strips from thigh-embracing positions to permit folding and placing said strips into concealment within said pockets.

LOUIS MINTZES.
